ADJUSTABLE TYPE GUIDE FOR
TYPEWRITERS

Fritz Eibert, Munich, Germany

Application March 26, 1932, Serial No. 601,407
In Germany December 29, 1931

2 Claims. (Cl. 197—43)

This invention relates to adjustable type guide for typewriters. The type lever is, in the course of time, worn off at the places where it comes into contact with the guide. In consequence of 5 the play caused by this, the distance between consecutive letters and the straightness of the line are adversely affected.

The present invention has the aim of overcoming this disadvantage. It has for its object an 10 adjustable type guide, which, as a unit or with its type shanks, can be displaced in the longitudinal direction of the type body of the type lever which has been struck. Whenever the type lever is 15 worn to the point of affecting the typing, the type guide as a unit, or the type shanks, are adjusted higher or lower, i. e. in the longitudinal direction of the type body of the type lever which has been struck, so that the type lever can be guided at 20 a place which has not been worn, without fault and without lateral displacement.

The adjustment device can be carried out in several ways. The drawing illustrates by way of an example two forms of application:

Fig. 1 shows a form of application in which 25 the whole type body can be adjusted as a unit.

Fig. 1a is a lateral view of Fig. 1, partly in section.

Fig. 1b is a plan view of Fig. 1, and

Fig. 2 is a second form of application, in which 30 a part which supports the guide shanks is adjustably arranged in the main body of the guide.

The guide *d* (Figs. 1 to 1b) acts, during the stroke of a type between its shanks *c*, as guide for the type lever *b*.

If the type lever *b* is worn off at A, owing to 35 repeated friction with the walls of the guide shanks *c*, so that on account of the thus created play the distance between the letters and the straightness of the type line are adversely affected, then the guide *d* is adjusted as a unit, inasmuch as, after the screws *h* are loosened, it is, 40 with the help of the slots *d*¹ adjusted vertically and/or horizontally in the longitudinal direction of the type body. After this adjustment of

the guide, the type lever will not come into contact with the guide walls at the place A but at the place B, and will again be correctly guided because a new and not worn part of the lever is being guided.

According to the form of construction shown in Fig. 2, the guide *d* is held fast in the usual way by two screws *h*. The guide shanks *c*, however, are in this case arranged on a special body *i* which is held in position by means of a clamp screw *g*, 10 in an undercut groove *f*, cut out from the front face of the guide *d*. In this case therefore not the whole guide is adjusted in a longitudinal direction of the type body, but, after loosening the screw *g*, the guide shanks *c* are adjusted with their 15 body *i* in the guide *d*.

I claim:

1. An adjustable and fixable type guide for typewriters which comprises a guide capable of being fixedly and permanently mounted on a support in front of a typewriter platen, an auxiliary member carrying a pair of shanks mounted on said guide, said auxiliary member being capable of vertical adjustment, and means for fixedly securing said auxiliary member in any adjusted 20 position, whereby the guide shanks can be moved from a region adjacent to a worn portion of a type lever to a region adjacent to an unworn portion of the type lever thereby insuring the correct guidance of the type lever to the typewriter 25 platen.

2. An adjustable and fixable type guide for typewriters which comprises a guide, a pair of shanks projecting from the upper part of said guide, and means associated with the lower part 30 of said guide for fixedly securing said guide in an adjusted vertical position, whereby the guide shanks can be moved from a region adjacent to a worn portion of a type lever to a region adjacent to an unworn portion of the type lever thereby 35 insuring the correct guidance of the type lever to the typewriter platen.

FRITZ EIBERT.
